UNITED STATES PATENT OFFICE.

PETER BAAR, OF CHICAGO, ILLINOIS.

WINDOW-VENTILATOR.

1,233,436.

Specification of Letters Patent. Patented July 17, 1917.

Application filed March 4, 1915. Serial No. 11,971.

To all whom it may concern:

Be it known that I, PETER BAAR, a citizen of the United States, residing at Chicago, in the county of Cook and State of Illinois, 5 have invented a certain new and useful Improvement in Window-Ventilators, of which the following is a full, clear, concise, and exact description, reference being had to the accompanying drawings, forming a part of 10 this specification.

My invention relates to ventilators and is particularly concerned with such devices which are adapted to be employed in connection with windows wherein vertically 15 movable sashes are employed. It is the object of my invention to provide a simple and effective device whereby vitiated air may pass from a room and be effectively replaced by fresh air from the outside atmosphere.

20 In accordance with the underlying theory of my invention, I provide a device adapted, in a sense, to cover a window opening, at the top of the window frame, this device having an outlet opening for vitiated air and an 25 inlet opening for fresh air, the vitiated air passing outwardly at the top of the window opening and the fresh air entering at the bottom of the window opening. In other words, due to the conformation and disposition 30 of the ventilator device of my invention, I provide for the passage of air in two directions through the window opening, passing outwardly at the upper portion thereof and inwardly at the lower portion 35 thereof. This window opening being preferably at the top of the sash, as hereinbefore explained, there is a complete avoidance of draft which might be injurious and the proper position of the outlet passage, for 40 the purposes of the expulsion of the vitiated air, is secured. Furthermore, the structure of my invention is such as to prevent the entry of rain or snow through the window opening and at the same time is such as to 45 have little, if any, effect upon the admission of light.

My invention is illustrated in the accompanying drawings in which—

Figure 1 is a front elevational view of the 50 device of my invention, parts being broken away to further illustrate the structure thereof.

Fig. 2 is a cross-sectional view taken on the plane of the line 2, 2, of Fig. 1 and looking in the direction indicated by the arrows,

this cross-sectional view being drawn on a somewhat larger scale.

Fig. 3 is a cross-sectional view showing the device of my invention applied to a window.

Fig. 4 is an elevational view of a modified form of my invention, and

Fig. 5 is a cross-sectional view showing the application of said modified form to a window.

Referring first to Fig. 3 it will be seen that the window frame 6 is supported in the usual way in the wall 7, the sashes 8 and 9 being properly guided for vertical movement in the frame by means of the strips 10, 11 and 12. Since this structure is thoroughly well known, no further description is necessary.

The device of my invention is primarily in the form of a canopy 13, presenting the 75 vertical front wall 15, the inclined wall 16 and the horizontal wall 17. The under side of the canopy is open, as indicated at 18. The inclined wall 16 is provided with an opening 19 in the form of a longitudinal slot, this opening being guarded by a baffle plate 20 extending upwardly from the lower edge of the opening 19. As a matter of convenience in construction, this baffle plate 20 may well be stamped from the opening 19 80 and then turned upwardly into the shape shown in Fig. 3. The particular structure of the canopy is thus illustrated in Fig. 1 where it will be seen that it is of general 85 telescoping structure so that it may be made to fit any window frame within reasonable limits. This structure is as follows:

The main canopy portion which has just been described fits at each end into an end structure which has vertical inclined and 95 horizontal walls 15^a, 16^a and 17^a corresponding to the walls 15, 16 and 17 of the main part of the canopy. The lower end of the wall 15^a and the inner end of the wall 17^a are turned inwardly as illustrated at 20' and 100 21 respectively (Fig. 2) and it will be seen that with this structure the main portion of the canopy can slide into the end structures and fit snugly within the turned portions of the wall.

105 The end pieces, which have just been described, provide the end walls 22, 22, and in the preferred embodiment of my invention, illustrated in Figs. 1, 2 and 3, these end walls are provided with openings 23, 23, 110

through which screws 24, 24, may be passed to secure the ventilator to the interior of the strips 10. In other words, this arrangement provides for the fit of the ventilator 5 close to the top of the opening and secured to the inner faces of the strips 10. As shown in Fig. 3, the upper sash is lowered to a point where the upper part thereof is approximately on a line with the lower part of 10 the canopy, thus providing a considerable opening at the top of the window frame. The vitiated air naturally hugs the ceiling of the room and also hugs the top of any passage through which such vitiated air may 15 move. Consequently the vitiated air of the interior of the room, on the right side of Fig. 3, will pass outwardly through the opening 25 at the top thereof, as indicated by the arrow 26 and will pass upwardly and 20 outwardly through the opening 19 and to the outside atmosphere as indicated by the arrow 27. At the same time, fresh air can enter through the open portion 18 of the canopy and will pass through the opening 25 at the bottom thereof as indicated by the arrow 28, thus supplying the interior of the room with fresh air. The baffle 20 prevents the entry of rain or snow through the opening 19 and through the opening 25. Any 30 rain or snow that falls upon the inclined wall 16 above the opening 19 will merely ride down the incline and drop through the opening 19 to the sill below.

It will be clear that in most window structures the air passing through the opening 25 at the bottom thereof may be supplemented by air entering between the two sashes as 35 illustrated by the arrows 29, 29.

In Figs. 4 and 5 I illustrate a modified 40 form. This modification is concerned merely with the attachment of the ventilator to the window frame. It will be seen that in these structures, I provide a face flange 30 extending laterally from the longer vertical

edge of the end walls 22, so that the canopy 45 can be secured to the face of the strip 10, instead of the interior faces thereof, if desired. In this structure a longitudinal flange 31 is also provided.

I claim as new and desire to secure by 50 Letters Patent:

1. A window ventilator in the form of a canopy, having an inclined wall, said canopy being open at the bottom and at the back and said inclined wall being provided with 55 an opening therein, and a baffle extending upwardly from the lower edge of said opening leaving the opening uncovered, the baffle thus directing upwardly air currents coming in contact therewith.

2. In combination a window frame, a canopy fitting within said frame at the top thereof, said canopy being open at the bottom and at the back and having an opening 60 in the front wall thereof, said opening being guarded by a baffle extending upwardly from the lower edge of said opening, said opening being uncovered, the baffle thus directing upwardly air currents coming in contact therewith.

3. A ventilator in the form of a canopy, having a vertical wall, an inclined wall, and a horizontal wall, end walls for said canopy, an opening in said inclined wall, and a baffle guarding said opening, said baffle extending upwardly from the lower edge of 75 said opening, and so arranged as to leave the opening uncovered, the baffle thus directing upwardly air currents coming in contact therewith, said canopy being secured over an 80 opening in a window frame by securing said end walls to said window frame.

In witness whereof, I hereunto subscribe my name this 1st day of March A. D. 1915.

PETER BAAR.
